US0D1011028S

(12) United States Design Patent (10) Patent No.: US D1,011,028 S
(45) Date of Patent: * Jan. 16, 2024

(54) HANDBAG

(71) Applicant: AUTUMNPAPER LIMITED,
Haywards Heath (GB)

(72) Inventor: Sarah Burton, London (GB)

(73) Assignee: AUTUMNPAPER LIMITED,
Haywards Heath (GB)

() Term: 15 Years

(21) Appl. No.: 29/833,687

(22) Filed: Apr. 6, 2022

(30) Foreign Application Priority Data

Oct. 8, 2021 (WO) WIPO109245

(51) LOC (14) Cl. 03-01

(52) U.S. Cl.
USPC D3/244

(58) Field of Classification Search

USPC D3/201, 232, 233, 234, 238, 240, 318,
